DESIGN FOR A COMBINED POKER CHIP
HOLDER AND CARD CASE

Joseph Foier, Brooklyn, N. Y.

Application March 27, 1946, Serial No. 127,997

Term of patent 3½ years

(Cl. D58—13)

To all whom it may concern:

Be it known that I, Joseph Foier, a citizen of the United States and a resident of Brooklyn, county of Kings, and State of New York, have invented a new, original, and ornamental Design for a Combined Poker Chip Holder and Card-case, of which the following is a specification, reference being had to the accompanying drawing, forming part thereof.

Figure 1 is a perspective view of a combined poker chip holder and card case in closed position, showing my new design;

I claim:

The ornamental design for a combined poker chip holder and card case, substantially as shown.

JOSEPH FOIER.
